[57] CLAIM

The ornamental design for a semi-rimless safety frame, as shown and described.

DESCRIPTION

FIG. 1 is a top plan view of a semi-rimless safety frame showing my new design;

FIG. 2 is a front elevational view thereof;

FIG. 3 is a rear elevational view thereof;

FIG. 4 is a bottom plan view thereof;

FIG. 5 is a right side elevational view thereof, with the left side elevation being a mirror image; and,

FIG. 6 is a perspective view thereof.
